UNITED STATES PATENT OFFICE

128,671

DESIGN FOR A BILLFOLD OR SIMILAR ARTICLE

Daniel Platkin, Los Angeles, Calif.

Application February 21, 1941, Serial No. 99,156

Term of patent 14 years

To all whom it may concern:

Be it known that I, Daniel Platkin, a citizen of the United States, residing in the city of Los Angeles, county of Los Angeles, State of California, have invented a new, original, and ornamental Design for a Billfold or Similar Article, of which the following is a specification, reference being had to the accompanying drawing, forming a part thereof.

Figure 1 is a top plan view of a billfold or similar article in open position embodying my design.

Figure 2 is an end view of the same as seen from the right hand side of Figure 1.

Figure 3 is a sectional view of the same taken on the line 3—3 of Figure 1.

The characteristic features of the design reside in the portions shown in full lines.

I claim:

The ornamental design for a billfold or similar article, as shown and described.

DANIEL PLATKIN.
